United States Patent Office

Des. 194,342
Patented Jan. 8, 1963

194,342

COMMERCIAL SIGN

Jon H. Daugherty, 5610 Willard Way, Riverside, Calif.

Filed June 29, 1961, Ser. No. 65,758

Term of patent 14 years

(Cl. D1—12)

FIGURE 1 is a perspective view taken from the front and one side of a commercial sign embodying my new design, the opposite side being a minor image thereof; and

I claim:

The ornamental design for a commercial sign, as shown and described.
